CORD CONNECTER BODY

Edward F. Bannon, Bridgeport, Conn., assignor
to Harvey Hubbell, Incorporated, Bridgeport,
Conn., a corporation of Connecticut

Application April 22, 1936, Serial No. 75,729

7 Claims. (Cl. 173—332)

This invention relates to new and useful improvements in electrical connectors and has particular relation to a cord connector body.

An object of the invention is to provide an electrical connector wherein the contacts are securely held against casual movement out of their respective proper places in the connector.

Another object is to provide in a connector including a contact mounting body and a casing receiving such body, cooperating means between the contacts and body for retaining the contacts in the body.

Other objects and advantages will become apparent from a consideration of the following detailed description taken in connection with the accompanying drawing wherein a satisfactory embodiment of the invention is shown. However it is to be understood that the invention is not limited to the details disclosed but includes all such variations and modifications as fall within the spirit of the invention and the scope of the appended claims.

In the drawing:

Fig. 1 is a partial side elevation and partial section, the section being taken substantially along the line 1—1 of Fig. 2;

Fig. 2 is a top plan view of the connector a part being broken away;

Fig. 3 is a view taken substantially along the line 3—3 of Fig. 4;

Fig. 4 is a bottom plan view of the connector body;

Figs. 5 and 6 are detail views showing a means employed for preventing relative turning of the body and casing of the connector;

Figs. 7 and 8 are elevational views at right angles to one another showing a contact employed;

Figs. 9 and 10 are views similar to Figs. 7 and 8 but showing a slight modification of contact construction employed for the ground connection; and

Fig. 11 is a sectional view showing the manner of inserting a contact in or removing a contact from the connector body.

Referring in detail to the drawing the invention is shown by way of illustration as embodied in a three wire cord connector including an insulating body 10 and an outer member or casing 11 receiving the inner end portion of said body. It is however also adapted for two wire connectors or single piece or other types of connectors. The casing 11 is also of insulating material and both it and the body are preferably molded of live rubber.

Body 10 is provided with recesses 12 mounting current contacts 13 and may also be provided with a similar recess 14 mounting a ground wire contact 15. The recesses 12 open through the inner end of the body 10 and terminate in radially extending openings or recesses 16 while the recess 14 also opens through the inner end of the body and terminates in an opening or recess 17. Entrance slots 18 are provided through the outer end wall of body 10 providing for the insertion into the respective body recesses of blade type contacts on connector caps.

The various recesses intermediate the ends of the body 10, immediately inwardly of the inner ends of the entrance slots, are laterally enlarged 15 as at 19 and such enlarged portions of the recesses are connected with the more restricted portions thereof by inclined side walls 20. In its inner end the body is provided with slots or recesses 21 extending laterally from the openings 20 16 and with a slot or recess 22 spaced from the opening 17 by a wall portion 23.

Each contact 13 includes a pair of elongated, finger-like, resilient members 24 and 25 detachably connected by a screw 26 which also serves 25 as a binding post screw for connecting a conductor as will be understood. The screw 26 threads into a hub portion 27 on the member 24 and clamps the inner end portions of the members 24 and 25 against one another. Member 24 is offset intermediate its ends as at 28 so that while the outer end portions of said members are normally in engagement at 29 they may be sprung apart in parallel relation by the insertion of a blade contact between them and will grip such blade contact and make a good electrical engagement with it. Beyond point 29 the members are bent to incline upwardly in opposite directions providing portions 30 extending away from one another, and the extreme ends of the members are 30 then again bent providing downwardly and outwardly inclined portions or flanges 31. In addition at its inner end member 25 is provided with lateral wing-like extensions 32.

Contact 15 includes one of the members 24 45 and also includes a member 25a corresponding in all respects with the member 25 except that member 25a does not include lateral wing-like extensions but does include an extension comprising a hook-like portion generally designated 50 33 and including a flat plate-like part 34 and a part or lug 35 at the outer edge of the part 34 and spaced from but substantially parallel with the main body of the member 25a.

When the contacts 13 are in their recesses in 55

the body their outwardly bent portions 30 are disposed in the laterally enlarged portions 19 of the recesses while the wing-like extensions 32 of the members 25 of the contacts occupy the slots 21 extending laterally from the openings 16. The disposal of the extensions 32 in the slots 21 provides a structure preventing the contacts from being pushed entirely through the recesses.

The laterally bent outer end portions 30 of the respective members of each contact are in engagement or are substantially in engagement with the side walls of the laterally enlarged portions 19 of the recesses 12 and thus overlie the inclined wall portions 20 of the recesses thereby preventing the contacts from falling out of the body or from being pushed out of the body through the inner ends of the recesses. On a blade contact being inserted through an entrance slot 18 it enters between the pair of members of a contact forcing such members apart and causing their extreme end portions 31 to have a greater effective width to thus engage inclined walls 20 of the enlarged recess portion 19, thereby still more effectively locking the contact in the body.

When a contact 15 is in place the plate 34 of its hook-like portion 33 overlies a part of the inner end of the body while its upturned part 35 enters the slot or notch 22 in such end of the body. This flat end 34 serves to easily distinguish the grounding contact from the other contacts when the electrician is making the lead wire connections, and indicating marks such for example as GR may be stamped on it if desired. Otherwise contact 15 functions in the same manner as the contact 13, the oppositely extending outer end portions of its members occupying the laterally enlarged portion of its recess to prevent the contact falling or being casually pushed out of place through the inner end of the body 10. Obviously the hook-like part 33 of the contact will prevent the latter being pushed too far into the body. It is to be understood that all of the contacts might be of the same construction and it is further to be understood that the invention is not limited to a connector mounting three contacts since obviously the ground contact may be omitted.

When the contacts are in place in the body they may not fall out of place or be casually pushed out of place, and in fact a contact may not be removed from the body except by removal of the screw 26 and withdrawal of the members or finger-like pieces thereof one at a time through the inner end of a body. The openings 16 and 17 give access either for the insertion or the removal of the screws 26.

Fig. 11 suggests the manner of applying or removing a contact, and in this connection it is pointed out that the contacts may be applied or removed only by detaching or releasing their members from one another by removing the screw 26 and then inserting the members one at a time into a recess through the inner end of the body 10 or removing such members one at a time through the inner end of the body. As shown in Fig. 11 screw 26 is absent and member 24 has either just been inserted into recess 14 and member 25a is being inserted after which the screw 26 will be applied, or it may be considered that screw 26 has just been removed and member 25a is being removed, after which member 24 may be easily removed. However the assembled contact can neither be applied nor removed.

After the contacts have been assembled in the

body 10 the inner end of the latter is inserted in the casing or cap 11 as shown in Fig. 1. Such casing includes a tubular extension 36 having an opening 37 therethrough for a conductor cable (not shown). On extension 36 is a cable clamp 5 comprising similar members 38 having ears 39 connected by screws 40 threaded into one clamp and adapted to be tightened to draw such members toward one another and thus clamp the tubular extension 36 against a cable passing therethrough and remove strain on the cable from the connection of the leads to the binding screws 26.

At the upper end of the casing 11 there is an annular inturned lip or bead 41 received in a groove 42 in the body 10 when the latter is partially inserted into the casing and inwardly of such bead 41 is a shoulder 43 against which the inner end of body 10 seats. The wing-like extensions 32 of contacts 13 and the plate-like part 34 of contact 15 also engage against this shoulder 43 and the shoulder thus serves to prevent such contacts moving or being pushed out of the body 10 when the body and casing are assembled. In one side such body is provided with a recess 44 and the casing 11 is provided with a corresponding projection or lug 45 entering the recess 44 when the casing and the body are assembled whereby the casing and body are held against relative turning movement.

Having thus set forth the nature of my invention, what I claim is:

1. A connector comprising an insulating body having a recess therein opening through its inner end and having an entrance slot in its outer end for the insertion of a blade type contact, said recess being enlarged in its portion immediately at the inner end of said entrance slot with a narrower portion inwardly of said enlargement, a contact in said recess and comprising a pair of separable resilient members and a screw connecting said members, and said members having their portions in the enlarged portion of the recess bent away from one another providing flanged portions of greater width than the narrowed portion of the recess to retain the contacts in the recess.

2. A connector comprising an insulating body having a recess therein opening through its inner end and an entrance slot through its outer end for the insertion of a blade type contact, said recess being laterally enlarged in its portion at the inner end of said entrance slot and having a narrower portion inwardly of said enlargement a contact in said recess and comprising a pair of members means detachably connecting the inner ends of said members, said members toward their outer ends substantially in engagement and laterally enlarged and extending into the enlarged portion of the recess whereby the contact is prevented from being pushed out of the body and can be removed therefrom only on separating said members and withdrawing them one at a time through the inner end of the recess and whereby on insertion of a blade type contact between said members they are forced apart at their extreme ends to cooperate with the walls of the enlarged portion of the recess to prevent longitudinal movement of the contact.

3. A connector comprising an insulating body having a recess therein opening through the inner end thereof and a blade type contact entrance slot leading to said recess from the outer end thereof, said recess being laterally enlarged intermediate the ends of the body, said body having a slot in

its inner end, a contact in said recess comprising a pair of connected members having laterally extending portions projecting into the laterally enlarged portion of the recess whereby to prevent movement of the contact out of the body through the inner end of the recess, an extension on one of said members and disposed in said slot at the inner end of the body to prevent movement of the contact outwardly through the recess, and means detachably connecting said members whereby they may be released from one another and removed one at a time through the inner end of the body.

4. A connector comprising an insulating body having a recess therein opening through the inner end thereof and a blade type contact entrance slot leading to said recess from the outer end thereof, said recess being laterally enlarged intermediate the ends of the body, a contact in said recess comprising a pair of separable members having laterally extending portions projecting into the laterally enlarged portion of the recess whereby to prevent movement of the contact out of the body through the inner end of the recess, means detachably connecting said members, and the narrower portion of said recess being of a width to permit removal of the members one at a time through the inner end of the recess after the members are disconnected.

5. A connector comprising a resilient insulating body having a recess therein opening through its inner end and having an entrance slot through its outer end for the insertion of a blade type contact, said recess being laterally enlarged in its portion at the inner end of said entrance slot, a contact in said recess comprising a pair of elongated resilient members, means detachably connecting said members at their inner ends, said members toward their outer ends being substantially in engagement and having their outer end portions bent away from one another and extending into the enlarged portion of the recess whereby the contact is prevented from being pushed out of the body and can be removed from the body only on detaching said members from one

another and withdrawing them one at a time through the inner end of the recess and whereby on insertion of a blade type contact through said slot between said members they are forced apart and their extreme ends caused to coact with the resilient walls of the enlarged portion of the recess to retain the contact in the recess. 5

6. A connector comprising an insulating body having a recess opening through the inner end thereof and an entrance slot leading to said recess from the outer end thereof, said recess being laterally enlarged intermediate the ends of the body, said body having a slot in its inner end spaced from said recess, a contact in said recess and comprising a pair of connected members having laterally extending portions projecting into the laterally enlarged portion of the recess whereby to prevent movement of the contact out of the body through the inner end thereof, a hook-shaped extension on one of said members and 10 having its end portion disposed in said slot in the inner end of the body and preventing movement of the contact outwardly through the recess, and means detachably connecting said members whereby they may be released from one another 15 and then removed one at a time through the inner end of the body.

7. A connector comprising an insulating body having a recess opening through its inner end and having an entrance slot leading to said recess 30 from the outer end of the body, said recess being laterally enlarged intermediate the ends of the body, a contact in said recess and comprising a pair of members having laterally extending portions projecting into the laterally enlarged portion of the recess whereby to prevent movement of the contact out of the body through the inner 35 end of the recess, means detachably connecting said members, and said means operable to connect said members after they have been inserted 40 into the body whereby they may be inserted one at a time through the inner end of the recess and then connected to prevent their casual removal from the body.

its inner end, a contact in said recess comprising a pair of connected members having laterally extending portions projecting into the laterally enlarged portion of the recess whereby to prevent movement of the contact out of the body through the inner end of the recess, an extension on one of said members and disposed in said slot at the inner end of the body to prevent movement of the contact outwardly through the recess, and means detachably connecting said members whereby they may be released from one another and removed one at a time through the inner end of the body.

4. A connector comprising an insulating body having a recess therein opening through the inner end thereof and a blade type contact entrance slot leading to said recess from the outer end thereof, said recess being laterally enlarged intermediate the ends of the body, a contact in said recess comprising a pair of separable members having laterally extending portions projecting into the laterally enlarged portion of the recess whereby to prevent movement of the contact out of the body through the inner end of the recess, means detachably connecting said members, and the narrower portion of said recess being of a width to permit removal of the members one at a time through the inner end of the recess after the members are disconnected.

5. A connector comprising a resilient insulating body having a recess therein opening through its inner end and having an entrance slot through its outer end for the insertion of a blade type contact, said recess being laterally enlarged in its portion at the inner end of said entrance slot, a contact in said recess comprising a pair of elongated resilient members, means detachably connecting said members at their inner ends, said members toward their outer ends being substantially in engagement and having their outer end portions bent away from one another and extending into the enlarged portion of the recess whereby the contact is prevented from being pushed out of the body and can be removed from the body only on detaching said members from one

another and withdrawing them one at a time through the inner end of the recess and whereby on insertion of a blade type contact through said slot between said members they are forced apart and their extreme ends caused to coact with the resilient walls of the enlarged portion of the recess to retain the contact in the recess. 5

6. A connector comprising an insulating body having a recess opening through the inner end thereof and an entrance slot leading to said recess from the outer end thereof, said recess being laterally enlarged intermediate the ends of the body, said body having a slot in its inner end spaced from said recess, a contact in said recess and comprising a pair of connected members having laterally extending portions projecting into the laterally enlarged portion of the recess whereby to prevent movement of the contact out of the body through the inner end thereof, a hook-shaped extension on one of said members and 10 having its end portion disposed in said slot in the inner end of the body and preventing movement of the contact outwardly through the recess, and means detachably connecting said members whereby they may be released from one another 15 and then removed one at a time through the inner end of the body.

7. A connector comprising an insulating body having a recess opening through its inner end and having an entrance slot leading to said recess 30 from the outer end of the body, said recess being laterally enlarged intermediate the ends of the body, a contact in said recess and comprising a pair of members having laterally extending portions projecting into the laterally enlarged portion of the recess whereby to prevent movement of the contact out of the body through the inner 35 end of the recess, means detachably connecting said members, and said means operable to connect said members after they have been inserted 40 into the body whereby they may be inserted one at a time through the inner end of the recess and then connected to prevent their casual removal from the body.
